UNITED STATES PATENT OFFICE.

OSCAR WOODWARD, OF MONTCLAIR, NEW JERSEY, ASSIGNOR TO YOST WRITING MACHINE COMPANY, OF ILION, NEW YORK, A CORPORATION OF NEW YORK.

TYPE-WRITING MACHINE.

No. 918,243.

Specification of Letters Patent. Patented April 13, 1909.

Application filed February 11, 1908. Serial No. 415,372.

To all whom it may concern:

Be it known that I, OSCAR WOODWARD, citizen of the United States, and resident of Montclair, in the county of Essex and State of New Jersey, have invented certain new and useful Improvements in Type-Writing Machines, of which the following is a specification.

My invention relates to typewriting machines and more particularly to tabulating mechanism and to means for controlling the speed of the carriage when it is released from its escapement mechanism.

Said invention consists of the features of construction, arrangements of parts and combinations of devices to be hereinafter described and claimed.

In the drawings, Figure 1 is a vertical front to rear sectional view of one form of typewriting machines embodying my invention, some of the parts unnecessary to an understanding of my invention being omitted. Fig. 2 is a vertical transverse sectional view of the same taken on a line $x-x$ of Fig. 1 and looking in the direction of the arrow at said line. Fig. 3 is a horizontal sectional view of the parts shown in Figs. 1 and 2, the section being taken on the line $y-y$ of Fig. 1 and looking in the direction of the arrow at said line. Fig. 4 is a fragmentary top plan view of a supporting bar and the carriage-retarding devices supported thereby. Fig. 5 is an enlarged detail longitudinal sectional view of the rotary device for controlling the speed of the carriage and the drum within which it is mounted. Fig. 6 is an enlarged detail fragmentary perspective view of the column stop bar and some of the associated parts. Fig. 7 is a detail perspective view with parts broken away of the cover plate for the reed frame. Fig. 8 is a like view of the reed frame with the reeds mounted therein. Fig. 9 is an enlarged detail fragmentary side or face view showing the opposite end of the column stop bar from that shown in Fig. 6 together with the means for supporting and effecting an adjustment of the bar. Fig. 10 is a fragmentary sectional view corresponding to Fig. 5 but showing another form of construction.

The frame of the machine comprises side plates 1, front and rear cross plates 2 and end corner posts 3 which support a top plate 4.

Fixed guide rolls 5 and 6 are grooved on opposite faces for coöperation with antifriction

balls 7 which likewise coöperate with oppositely disposed grooved carriage rails 8 and 9 which form part of a carriage truck 10 that supports a superposed carriage structure comprising side plates 11 connected by parallel links 12 with a platen frame 13 which supports a cylindrical platen 14.

So far as the present invention is concerned the carriage may be of any suitable construction; that shown in the present instance being similar in some respects to that disclosed and claimed in my application Serial No. 362,734, filed March 16th, 1907. Depending ears 15 are formed on the carriage truck and three arm levers 16 are pivoted to these lugs at 17. The forwardly extending arms 18 of the levers co-act with screw stops 19, whereas the rearwardly extending arms 20 coöperate with downwardly pressing leaf springs 21 (see Figs. 1 and 2) which are secured to the truck by screws 22. The depending arms 23 of said levers are connected to a horizontally disposed feed rack 24 by screws 25. The construction is such that in the normal position of the parts the arms 18 of the lever 16 are forced into contact with the screw stops 19 as shown in Fig. 1 by pressure of the springs 21. This carriage release mechanism is shown and claimed in my application Serial No. 415,373, filed February 11th, 1908.

The printing mechanism may be of any suitable construction, that shown in the present instance being of a general character such as that shown in the application of A. W. Smith, Serial No. 295,801, filed January 12th, 1906.

The various parts of the printing instrumentalities are mounted in an auxiliary frame 26 which is detachably secured to the main frame of the machine. Key levers 27 are pivoted on a pivot rod 28 connected at its ends to rearwardly extending arms 29 of the auxiliary frame 26. Each of these key levers is provided with a finger key 30 and is guided at its forward end in a saw-kerf or slot 31 formed in the vertically disposed side or member of an angular plate 32 which is bent rearwardly to form a horizontally disposed portion 33 provided with an upwardly bent flange 34 at its rear edge by which the angular plate is secured in the auxiliary frame by screws 35 near each end of the plate. Each key lever is pivotally connected at 36 to a link 37 pivoted to a bell crank lever 38 supported by a hanger 39 on a seg-

ment 40 which forms part of the auxiliary frame. A rearwardly projecting link 41 extends from the upright arm of the bell crank rearwardly to a driver 42 pivoted at 43 on a hanger 44 secured to a segment 45 which is carried by the auxiliary frame 26. The driver 42 is pivoted at 46 to a type bar 47. The forward end of the type bar is pivoted at 48 to a guide link 49 which in turn is pivoted at 50 on a pivot wire which is seated in a groove in a segment 51, each guide link 49 working in a radial slot 52 cut in the segment 50. A depression of a key lever 27 effects an actuation of the corresponding driver 42 which effects a movement of the type bar from the normal position where the types rest against an ink pad to the operative or printing position, during which movement the lowercase type will follow a path indicated by the dotted line *a* in Fig. 1.

The angular plate 32 hereinbefore referred to is provided with a series of guide openings 53 (see Fig. 3) in the top or horizontally disposed portion 33 thereof. These openings receive the key stems 54 of denominational tabulator keys 55 and guide them in their vertical movement. The lower ends of the key stems 54 are guided in similar openings in an angular plate 56 secured at its ends to the frame of the machine by screws 57. It will be seen from this construction that the row of denominational tabulator keys are arranged in the keyboard of the machine and constitute the last row or bank thereof.

A series of angular denominational levers 58 are pivoted and extend beneath the printing key levers as shown in Fig. 1 and each of the levers 58 extends at its forward end through an opening in the associated key stem 54. The levers 58 all extend rearwardly, and for a short distance are parallel with each other and then flare inwardly toward each other and toward the center of the machine where they are bent at 59, thence extending rearwardly and upwardly, forming upright parallel members 60 provided at their upper ends with denominational stop portions 61 so that each lever 58 comprises a horizontally disposed portion and an upwardly and rearwardly extending portion 60 provided at the upper end thereof with the stop member or portion 61. The various levers 58 are supported on a pivot rod 62 which passes through depending flanges 63 formed on or connected with a cross bar 64 that is supported at its ends upon inwardly extending lugs 65 which project from the side plates of the main frame. This cross bar is secured to lugs by screws 66. The pivot rod 62 is secured in its bearing by screws 62^a. The depending supporting portion 63 of the cross bar 64 is formed with slots in which the levers 58 are received and in which they work, thus maintaining the levers properly spaced apart at those por-

tions thereof which are pivoted to the cross bar. The upper end of each denominational lever 58 is received in a slot or opening 67 formed between two adjacent reed bars 68 which are clearly shown in Fig. 8. These 70 reed bars are received in slots 69 in a frame 70 which is rectangular in form and has a central rectangular opening through which the levers 58 extend as they pass through the slots between the reed bars.

A cover or cap plate 71 is provided with depending ends and sides 72, the sides abutting the ends of the reed bars and that portion of the frame in which they are seated. A top 73 of the cap or cover plate bears on 80 top of the reed bars, thus forming a means for preventing a displacement of the reed bars on the frame 70 on which they are carried. Screws 74 (Fig. 2) extend through openings 75 and 76 in the corners of the 85 cover plate and frame 70 respectively and take into threaded openings in the top plate 4 of the machine so that the same screws 74 which secure the cap plate or cover in place also secure the frame 70 in place. The cover 90 plate has a rectangular central opening 77 therein which, when the cover plate is in place, is substantially coincident with the central rectangular opening in the frame 70. A like rectangular opening 78 is formed in 95 the top plate coincident with the rectangular openings in the frame 70 and cover plate 71 so that the stops 61 or their actuating levers may extend through the coincident openings in the top plate, in the frame 70 100 and in the cover plate 71, and are guided in the slots 67 between the reed bars 68 in the movements of the stops toward and from the front of the machine. By this construction the parts can be readily assembled and yet undivided bars 68 are provided between the denominational stop levers and strong and rigid means are provided to resist the denominational stops when an impact of the carriage against said stops takes place.

Each denominational key lever is connected to one end of a contractile spring 79 (Figs. 1 and 3), and the other end of said spring being connected at 80 to an angular plate 81 secured to the rear cross plate 2 of 115 the machine by rivets 82.

Brackets 83 and 84 (Fig. 2) are secured by screws 85 to upwardly projecting lugs 86 on the carriage truck. The brackets 83 and 84 constitute bearings and supports for a column stop bar 87 grooved on opposite sides as at 88 for coöperation with bifurcated plate-like column stops 89. The right-hand bracket 84 as shown in Fig. 6 is provided with an inclined angular opening or seat 120 90 for coöperation with an angular portion 91 of the column stop bar to prevent said bar from turning in its bearings and to maintain the stop bar and the stops carried thereby inclined on the carriage as shown in 130

Fig. 1. A cylindrical stem or extension 92 is received in a corresponding opening in the bracket 84. The opposite end of the column stop bar as shown in Fig. 9 is provided with a threaded end 93 which passes freely through an opening in the bracket 83 and is provided with a nut 94 on the outer side of the bracket and a thumb nut 95 on the inner side of the bracket. These nuts afford a longitudinal adjustment of the column stop bar in its bearings and by screwing the nuts up tight against the bracket 83, the stop bar may be rigidly secured in its adjusted position. From an inspection of Figs. 1 and 6 it will be seen that each of the column stops 89 is provided with a forwardly extending projection or abutment 96 against which the lower edge of a locking plate 97 is adapted to bear. This locking plate is pivoted to brackets 83 and 84 as indicated at 97^a so that it may be swung forwardly when desired to carry the lower free end or edge of the locking plate away from the abutments 96 on the column stops and enable them to be detached from the stop rod. When, however, the locking plate is in the position shown in Figs. 1 and 6 it prevents a detachment of any of the column stops. A finger piece 98 is secured by screws 99 to the locking bar to facilitate a movement of the locking bar to the inoperative position, whereas a coiled spring 100 (see Fig. 2) is operative to move the locking bar to the operative or locking position.

From the foregoing description it will be understood that a depression of any of the denominational keys 55 will move the corresponding denominational stop 61 upwardly and forwardly in an inclined path or arc of which the pivot 62 is the center and into the path of the stopping portion 101 of the column stops carried by the carriage.

In order to effect a release of the carriage by an actuation of any of the denominational keys and at the same time to automatically throw the means for controlling the speed of the carriage into operation, I provide a universal bar 102 which extends beneath the forward ends of the levers 58 as shown in Figs. 1 and 3. This universal bar is formed with rearwardly projecting side members 103 which are riveted at 104 to forwardly projecting arms 105 formed as a part of a cross bar or member 106. The arms 105 are pivoted at 107 to forwardly projecting lugs or brackets 108 connected to or formed on the cross bar 64 hereinbefore referred to. The right-hand arm 105 is extended rearwardly to form an arm 109 which is connected to the lower end of an upright link 110 (see Figs. 1 and 2). Said link is connected at its upper end to a crank arm 111 (see Figs. 1, 2 and 4) projecting from the rock shaft 112 which carries and may be formed as a part of a drum 113. The rock shaft 112 is supported at its ends by coned bearing studs 114 which ex-

The drum and cap form an inclosed chamber in which a rotary carriage-speed-controlling device is contained. This device comprises a shaft 121 which rotates in a bearing sleeve 122 formed as a part of the drum and has crossed blades, wings or arms 123 secured thereto. The upper end of the shaft 121 which extends beyond the sleeve 122 has a pinion 124 secured thereto by a pin 125 which extends through the hub of the pinion and through the shaft 121. Any suitable material may be contained within the drum such, for instance, as plumbago and shot or shot alone. The sleeve 122 is provided at its outer end with an off-set arm 126 (see Fig. 4) to which an arm or finger 127 is secured by a screw 128. The contact face of the arm or finger 127 is adapted to bear against the ends of the teeth of the carriage feed rack 24 so that when the drum, which is pivoted at substantially right angles to the axis of rotation of the rotary device, is swung to the operative position the finger forces the feed rack around its pivots 17 and out of mesh with a feed pinion 129 which is operatively connected with suitable escapement mechanism (not shown), thereby releasing the carriage from its escapement mechanism. The relation of the parts is such that the same movement which effects a disengagement of the rack from its feed pinion also carries the pinion 124 into mesh with the feed rack and controls the depth of engagement between the teeth of the feed rack 24 and the pinion 124. The carriage rack being released in the manner described is brought into mesh with the pinion 124 which is rotated by the power of a spring drum 130 connected to the carriage by a cord 131 and the rotary device within the drum is turned and a retarding effect is produced to control the speed of the carriage in its movement in the direction of its feed movement when the tabulating mechanism is actuated and the carriage is free from its escapement mechanism.

In Fig. 10 I have shown another form of construction of carriage retarding device which is mounted and controlled in the manner hereinbefore described. It is the same as the structure formerly described except that the cap or cover 120^a has a shorter flange and the cap may be adjusted farther in the drum 113^a in order to exert more or less pressure on the mass of material contained within the drum and thus offer more 130

or less resistance to the turning movement of arms 123^x which do not extend from edge to edge substantially to the walls of the drum and cap as in the structure previously described to push the mass of material in the drum ahead of them but the arms 123^x are forced through the material. The shaft 121^x in Fig. 10 does not extend so far through the drum as in the previously described structure and is provided with a collar 122^x to prevent the withdrawal of the shaft from the drum in one direction.

A leaf spring 132 (Fig. 4) is connected to and carried by the projection 126 of the drum 15 and bears against a projection 133 on the cross bar 116 so that this spring is flexed when the drum is swung on its pivots to release the carriage and restores the drum to normal position when pressure on a tabulator key is released.

From the foregoing description it will be seen that the pull of the spring drum is exerted on the carriage about centrally thereof and about centrally between the bearings for 25 the carriage where the pull is most effective and buckling or side strain on the bearings of the carriage is avoided; that the feed rack is likewise located between the carriage bearings and coöperates with the escapement 30 mechanism at such point and likewise avoids side or cross strains on the bearings; that the carriage retarding device is likewise brought into coöperation with the carriage between its bearings so that the resistance offered by 35 said retarding device does not offer or cause any side or lateral strains to be exerted on the carriage bearing but exerts its resistance substantially in line with the pull on the carriage.

40 Various changes may be made without departing from the spirit and scope of my invention.

What I claim as new and desire to secure by Letters Patent, is:—

45 1. In a typewriting machine and tabulating mechanism, the combination of denominational stop actuating devices, and guiding means therefor, said guiding means comprising independent reed bars, and means for detachably and independently connecting said independent reed bars with the machine and for holding them against accidental displacement thereon.

55 2. In a typewriting machine and tabulating mechanism, the combination of denominational stop actuating devices, and guiding means therefor, said guiding means comprising independent reed bars, a frame in which said reed bars are removably seated, and a 60 detachable cover for securing said reed bars in place.

3. In a typewriting machine and tabulating mechanism, the combination of denominational stop actuating devices, and guiding 65 means therefor, said guiding means comprising

ing independent reed bars, a frame in which said reed bars are removably seated, and a detachable cover for securing said reed bars in place, said cover being in the form of a rectangular frame that is adapted to bear 70 against the sides and ends of the reed bars and to prevent a movement of the reed bars in the frame in which they are seated.

4. In a typewriting machine and tabulating mechanism, the combination of denominational stop actuating devices, and guiding means therefor, said guiding means comprising independent reed bars, a frame having parallel grooves in which said reed bars are seated, and a cover plate or frame having an 80 open center through which said stop actuating devices are guided between the reed bars and which bears against the reed bars at the sides and ends thereof and prevents a displacement of the reed bars from the frame 85 in which they are seated.

5. In a typewriting machine and tabulating mechanism, the combination of denominational stop actuating devices, and guiding means therefor, said guiding means comprising independent reed bars, a frame in which said reed bars are removably seated, a detachable cover for securing said reed bars in place, and screws which secure the cover plate in place on the machine, the same 95 screws which secure the cover in place also securing the said frame in place.

6. In a typewriting machine and tabulating mechanism, the combination of a carriage, and means for retarding the movement 100 of the carriage in the direction of its feed when the carriage is freed from its escapement mechanism, said means comprising a rotary device situated beneath the carriage, a drum in which the rotary device works, a 105 horizontally swinging feed rack on the carriage situated beneath the same about midway between the bearings for the carriage, and key actuated means for swinging said drum and rotary device and bringing the 110 latter into coöperation with said feed rack.

7. In a typewriting machine and tabulating mechanism, the combination of a carriage, and means for retarding the movement 115 of the carriage in the direction of its feed when the carriage is freed from its escapement mechanism, said means comprising a rotary device situated beneath the carriage, a pivoted drum by which the rotary device is carried and in which it works; the pivotal 120 axis of the drum being at substantially right angles to the axis of rotation of said rotary device, a feed rack on the carriage, said feed rack being situated beneath the carriage about centrally of the bearings therefor, and 125 key actuated means for swinging said drum and rotary device and bringing the latter into coöperation with said feed rack.

8. In a typewriting machine and tabulating mechanism, the combination of a carriage, 130

- and means for retarding the movement of the carriage in the direction of its feed when the carriage is freed from its escapement mechanism, said means comprising a cross bar or support secured to the frame of the machine beneath the carriage, a drum carried by and pivoted to swing on said cross bar, a rotary device carried by and working within said drum, a pinion connected with 5 said rotary device, a feed rack carried by the carriage and extending beneath the carriage longitudinally thereof and about midway between the carriage bearings, and key actuated means for swinging said drum and moving the pinion into mesh with said feed rack.
9. In a typewriting machine and tabulating mechanism, the combination of a carriage, and means for retarding the movement of the carriage in the direction of its feed 10 when the carriage is freed from its escapement mechanism, said means comprising a drum pivotally supported beneath the carriage, a rotary device which is carried by and rotates within said drum, a pinion carried 15 by said rotary device, a feed rack carried by and beneath the carriage, a feed device normally engaged by said pinion, and an arm carried by said drum and co-operative with said feed rack to move it out of engagement 20 with said feed device after the said pinion has been brought into mesh with said feed rack.
10. In a typewriting machine and tabulating mechanism, the combination of a carriage, denominational stop mechanism comprising a column stop bar carried by the carriage, a plurality of denominational stops co-operative with said column stops, key actuated levers for the denominational stops, 25 a universal bar extending beneath said key actuated levers, a drum situated beneath the 30 carriage, a rotary device which turns in said drum, a pinion carried by said rotary device, a feed rack carried by and beneath said carriage, and connections between said drum and said universal bar, whereby when a denominational key is depressed the feed rack 35 will be engaged by said pinion and the rack will be moved laterally to disengage it from the carriage feed mechanism. 45
11. The combination of printing instrumentalities, key levers for actuating the same, a main machine frame, an auxiliary frame, tabulating mechanism, key stems for actuating the same, a combined reed and 50 guide plate, one portion of said plate being slotted to form a reed to guide said key levers and another portion of said plate being perforated to receive and guide said key stems, and means for detachably securing 55 said plate in place on said auxiliary frame. 60
12. The combination of printing instrumentalities, key levers for actuating the same, a main machine frame, an auxiliary frame, tabulating mechanism, key stems for actuating the same, a combined reed and 65 guide plate, one portion of said plate being slotted to form a reed to guide said key levers, and another portion of said plate being bent at substantially right angles to said first 70 mentioned portion and being perforated to receive and guide said key stems, and means for detachably securing said plate in place on said auxiliary frame. 75

Signed at the borough of Manhattan, city of New York, in the county of New York, and State of New York, this 10th day of February A. D. 1908.

OSCAR WOODWARD.
